CLAIM

The ornamental design for an apparatus for carrying suspended items, as shown and described.

DESCRIPTION

FIG. 1 is a perspective view of the apparatus for carrying suspended items in accordance with the present invention; and,

FIG. 2 is a perspective environmental view showing a shoulder strap attached to the apparatus of FIG. 1 for purposes of hands-free carrying of bags that may be suspended from the apparatus.

The broken line showing of environmental structure is for purposes of illustrating the claimed design in condition of use. The broken lines and structure they depict form no part of the claimed design.
